BICYCLE CHAIN COVER

Loran R. Hill, Olney, Ill., assignor to American Machine & Foundry Company, a corporation of New Jersey

Filed Feb. 10, 1969, Ser. No. 15,707

Term of patent 14 years

Int. Cl. D12—14

U.S. Cl. D90—5

FIG. 1 is a perspective view of a bicycle chain cover of my design; and

FIG. 2 is another perspective view of the chain cover.

I claim:

The ornamental design for a bicycle chain cover, substantially as shown.
